POWDER AEROSOL

Daniel C. Geary, Westwood, N.J., and Robert D. West, Ossining, N.Y., assignors to Union Carbide Corporation, a corporation of New York
No Drawing. Filed May 23, 1960, Ser. No. 31,228
18 Claims. (Cl. 167—82)

This invention relates to a novel powder aerosol system. More specifically, this invention relates to a novel powder aerosol formulation which enables at least 15 percent by weight of active powder to be dispensed in a conventional aerosol bomb.

The use of aerosol bombs to dispense various substances has become extremely popular in recent years. Products such as anti-perspirants, bath salts, dandruff remedies, hair dyes, hair shampoos and hair waving preparations have been packaged in aerosol containers.

However, in these conventional aerosol formulations, the active powder is only ten percent by weight of the total weight of substances packaged in the container. The balance of the weight is made up by the propellant and various other substances such as surfactants, perfumes, etc. The art has strived to increase the amount of active powder which can be dispensed but heretofore has been unsuccessful. When the active powder was increased beyond 10 percent by weight, it resulted in valve clogging or leakage which caused the propellant to escape without dispensing any powder. In addition, the increase in active powder beyond the ten percent range caused agglomeration of the powder on long standing with the result that no solid could be dispensed even after shaking the container.

In an attempt to solve the problem, the art reduced the particle size of the active powder. However, the active powder had to be reduced to a diameter no greater than 9 microns in order to be able to successfully dispense more than ten percent by weight. This reduction of particle size led to serious disadvantages such as the need for expensive equipment and increased costs of manufacture. Additionally, the use of powders having such small diameters resulted in sprays which were too fine so that they remained in the air and did not properly settle on the surface being sprayed. In addition, the use of particles which are too small leads to a serious health problem since they contaminate the sprayers' lungs.

Accordingly, it is the primary object of this invention to provide a system wherein at least 15 percent by weight of any active powder, having a particle diameter of at least 15 microns, can be dispensed with adequate regularity.

It is also an object of this invention to provide an aerosol system free of any substantial agglomeration of powder.

It is still another object of this invention to provide a basic system capable of dispensing any powder or powders in concentration of at least 15 percent by weight, based on the total formulation, provided the powder or powders are at least 15 microns in diameter.

These objects have now been found to be attained when a critical balance is maintained between the volumes of the various substances in an aerosol bomb.

In the basic powder aerosol system of this invention,

2

a definite criticality exists in the presence, and volume of, certain ingredients.

It has now been found that if a surfactant, a bulking agent, a non-polar liquid and a propellant are combined in a certain critical ratio by volume, any active powder having a diameter of at least 15 microns can be dispensed in quantities of at least 15 percent by weight. The preferred embodiment is to dispense at least 25 percent by weight of active powder.

10 The system of this invention can be illustrated by the following formula:

$$YX = A + B + C + D$$

where X represents the volume of the active powder or powders at atmospheric pressure minus the volume of the powder or powders at the maximum yield point. By maximum yield point is meant that point at which there is an increase in strain without a corresponding increase in stress. This term is defined in Mechanics of Material by E. P. Popov, Prentice-Hall, p. 30-31. In the formula, A represents the percent by volume of XY of the bulking agent; B represents the percent by volume of XY of the non-polar organic liquid; C represents the percent by volume of XY of the propellant; D represents the percent by volume of XY of the surfactant; and Y is any number from 1 to 10, including fractions. Thus, Y can be a number between 2 and 5.

15 The following table will illustrate the critical concentrations of the above ingredients. The values represent 20 percent by volume of XY .

30 TABLE I

35	A (bulking agent)	B (non-polar liquid)	C propellant	D surfactant
Maximum-----	60	70	67	10.5
Minimum-----	1	2	9	0.6
Preferred range-----	20-40	6-30	10-65.5	1.2-4

40 Thus, it can be seen that merely by knowing the volume at atmospheric pressure and at the maximum yield point of an active powder or mixture of powders, a powder aerosol system capable of dispensing at least 15 percent by weight of the desired active powders, can be formulated.

45 As can be seen from the formula, the volume occupied by the bulking agent, surfactant, non-polar organic liquid, and propellant is from one to 10 times that volume which is the difference in volume of the powder at atmospheric pressure and the volume at the maximum yield point. However, our preferred embodiment is when the total volume of propellant, non-polar organic liquid, surfactant and bulking agent is from 4-8 times X .

50 The particular active powder or powders which can be dispensed in the aerosol system of this invention, are practically unlimited. The nature of these powders is not critical. The only limitation is the particle size. The diameter of the powders must be at least 15 microns. The preferred particle diameter is from 15 to 100 microns.

55 The following table will illustrate some of the numerous formulations which can be dispensed by the system of this invention. It is to be understood that this table is only illustrative of the many uses to which this novel powder aerosol system can be placed. The active pow-

ders set forth under the various headings can be used alone or in combination with each other.

TABLE II

Type of Formulation	Active Powder
Tooth Powder.....	dicalcium phosphate. anhydrous dicalcium phosphate. hydrated dicalcium phosphate. tricalcium phosphate. calcium sulfate. calcium carbonate. aluminum sulfocarbonate. zinc sulfocarbonate. aluminum chlorohydrol. aluminum sulfate. aluminum chloride. zinc sulfate. zinc chloride. zirconium chloride. hexachlorophene and talc.
Anti-Perspirants.....	
Catamenial napkin powder or Body Powder.....	
Foot Powder.....	talc and dichlorophene.
Polish.....	talc and a salt of undelaic acid. pumice and a detergent.

It is to be understood that the presence of conventional amounts of other ingredients does not affect the novel powder aerosol system. Thus, when making a body powder, small amounts of perfume can be added as is customarily done in this type of formulation. Additionally, small amounts of water can be added when making antiperspirants, as is also conventional in this type of formulation.

The nature of the bulking agent is also not critical. It can be any powder which does not affect the intended use of the aerosol formulation. The only practical limitation of the bulking agent is that it must have a particle size no bigger than that of the active powder being dispensed. Examples of these bulking agents include silicon dioxide, powdered mica, clay, flour, etc.

As a further illustration that the nature of the bulking agent is not critical, the following example is given.

Assuming that an aerosol bomb was desired to dispense a foot powder whose active ingredient was talc. If the talc employed was composed of particles which had a diameter of 50 microns, the bulking agent could also be talc having a particle size of 20 microns.

Thus, it can be seen that the nature of the bulking agent is not critical but its presence is.

The organic liquid which is also necessary in the present system can be any non-polar organic liquid which is miscible in all proportions with the surfactant and propellant, which reduces the cohesive force of the active powder particles and which is an electrical insulator. The reason why this liquid must be an electrical insulator to operate in the system of this invention is not understood. The fact remains that liquids which act as conductors will not be operable. Examples of operable substances include any hydrophobic oil or ester having a specific gravity of 1.6 or less, and liquid hydrocarbons such as hexane, heptane, octane, etc. The preferred liquid is a mineral oil having a specific gravity of 0.9 or less. The esters which are operable include the esters of monocarboxylic acids having from 2-18 carbon atoms and monohydric alcohols having from 1 to 18 carbon atoms. Of these esters, the ones which are especially desirable are those of monocarboxylic acids having from 10 to 18 carbon atoms. Specific examples of these esters include butyl stearate, propyl myristate, pentyl laurate, ethyl caprate, etc.

The propellant can be any conventional propellant used in aerosol containers. These propellants include hydrocarbons, fluorocarbons, and compressed gases. Specific propellants include compressed air, nitrogen, carbon dioxide, C_1 to C_5 hydrocarbons, Cl_3FC , Cl_3F_2C and any tetrafluoroethane.

The surfactants employed in the powder aerosol system can be any nonionic, anionic, cationic or ampholytic surfactants include the sorbitan derivatives. Other opera-

ble surfactants are those surfactants on pages 191 to 194 and 338 to 367 of Emulsions: Theory and Practice by Becher, published by the Reinhold Publishing Corporation (1957), which are liquids.

It is also to be understood that the shape and size of the aerosol container as well as the size of the spray nozzle are not critical. Any conventional package can be employed.

The following examples illustrate the invention. The volume is in cubic feet at atmospheric pressure.

EXAMPLE 1 (Tooth Powder)

	Formulation 10-53	Percent by Wt.	Volume, cu. ft.
15	Dicalcium Phosphate (anhydrous).....	25.0	0.286
	Santocel 54.....	1.5	0.036
	Blandol.....	10.0	0.187
	Span 85.....	2.5	0.042
20	"Ucon" Propellant 12/114 40/60.....	61.0	0.690

In the above example, the volume of dicalcium phosphate at atmospheric pressure is 0.286 cubic foot. The volume at maximum yield point is 0.139 cubic foot.

25 Thus, X is equal to $(0.286 - 0.139)$ 0.147 cubic foot. Substituting X in the general formula gives the following:

$$\begin{aligned} 0.147y &= A+B+C+D \\ &= 0.395+0.187+0.69+0.042 \\ &= 1.314 \\ y &= 8.94 \end{aligned}$$

Percent by volume of A, B, C and D to XY

$$A = \frac{0.395}{1.314} \times 100 = 30.1$$

$$B = \frac{0.187}{1.314} \times 100 = 14.2$$

$$C = \frac{0.69}{1.314} \times 100 = 52.4$$

$$D = \frac{0.042}{1.314} \times 100 = 3.3$$

EXAMPLE 2 (Tooth Powder)

		Percent by Weight	Volume in Cubic Feet
45	Dicalcium phosphate anhydrous.....	2.50	0.029
	Dicalcium phosphate dihydrate.....	22.50	0.489
50	Santocel 54.....	1.75	0.461
	Klearol.....	10.50	0.202
	Span 85.....	0.80	0.013
	Tween 80.....	0.40	0.006
	Flavor.....	0.50	0.004
	"Ucon" propellant 12/114/90/10.....	61.05	0.722

55 In the above example, the total volume of the active powders at atmospheric pressure is 0.518 cubic foot. The total volume of the powders at maximum yield point is 0.170 cubic foot. Thus X is equal to $(0.518 - 0.170)$ 0.348. Substituting X in the formula gives the following:

$$\begin{aligned} XY &= A+B+C+D \\ .348Y &= 0.461+0.202+0.722+0.019 \\ .348Y &= 1.404 \\ Y &= 4.04 \end{aligned}$$

Percent by volume of A+B+C+D to XY

$$A = \frac{0.461}{1.404} \times 100 = 32.8$$

$$B = \frac{0.202}{1.404} \times 100 = 14.3$$

$$C = \frac{0.722}{1.404} \times 100 = 51.4$$

$$D = \frac{0.019}{1.404} \times 100 = 1.5$$

5

EXAMPLE 3
(Body Powder)

	Percent by Weight	Volume in Cubic Feet
Talc	20.0	0.354
Santocel 54	1.0	0.263
Carnation Oil	5.0	0.095
Span 85	0.4	0.007
Hexachlorophene	0.2	0.095
Perfume	0.2	0.001
"Ucon" Propellant 12	26.6	0.443
"Ucon" Propellant 114	26.6	0.397

In the above example the volume of the active powder at atmospheric pressure is 0.354 cubic foot. The volume at the maximum yield point is 0.120 cubic foot. Thus X is equal to $(0.354 - 0.120)$ 0.234. Substituting X in the formula gives the following:

$$0.234Y = 0.263 + 0.095 + 0.840 + 0.007$$

$$0.234Y = 1.205$$

$$Y = 5.1$$

Percent by volume of A, B, C and D to XY

$$A = \frac{0.263}{1.205} \times 100 = 21.8$$

$$B = \frac{0.095}{1.205} \times 100 = 7.9$$

$$C = \frac{0.840}{1.205} \times 100 = 69.7$$

$$D = \frac{0.007}{1.205} \times 100 = 0.6$$

EXAMPLE 4

(Foot Powder)

	Percent by Weight	Volume in Cubic Feet
Talc	25.0	0.442
Santocel 54	1.50	0.395
Zinc Stearate	0.50	0.060
Dichlorophene	0.20	0.095
Klearol	5.00	0.096
Perfume	0.20	0.002
Propellant 12	34.05	0.408
Propellant 11	34.05	0.364
Span 85	0.8	0.014

In the above example, the volume at atmospheric pressure of the active powder is 0.442 cubic foot. The volume of the active powder at maximum yield point is 0.150 cubic foot. Thus, X is equal to $(0.442 - 0.150)$ 0.292. Substituting X in the general formula yields the following:

$$0.292Y = A + B + C + D$$

$$= 0.490 + 0.096 + 0.772 + 0.014$$

$$= 1.372$$

$$Y = 4.7$$

Percent by volume of A, B, C and D to XY

$$A = \frac{0.490}{1.372} \times 100 = 35.7$$

$$B = \frac{0.096}{1.372} \times 100 = 7.0$$

$$C = \frac{0.772}{1.372} \times 100 = 56.2$$

$$D = \frac{0.014}{1.372} \times 100 = 1.0$$

6
EXAMPLE 5
(Anti-Perspirant)

5		Percent by Weight	Volume in Cubic Feet
Aluminum Chlorohydrol—40 microns	25.0	0.483	
45 Oil	8.0	0.156	
Span 85	0.8	0.013	
Santocel 54	1.75	0.461	
Tween 80	0.4	0.006	
"Ucon" Propellant 12/14 40/60	64.0	0.724	

In the above example, the volume of the active powder at atmospheric pressure is 0.483 cubic foot. The volume of the active powder at the maximum yield point is 0.166 cubic foot. This X is equal to $(0.483 - 0.166)$ 0.317. Substituting X in the general formula yields the following:

$$20 \quad 0.317Y = A + B + C + D$$

$$= 0.461 + 0.156 + 0.724 + 0.019$$

$$= 1.360$$

$$Y = 4.28$$

25 Percent by volume of A, B, C and D to XY

$$A = \frac{.461}{1.36} \times 100 = 33.9$$

$$B = \frac{0.156}{1.36} \times 100 = 11.5$$

$$C = \frac{0.724}{1.36} \times 100 = 53.2$$

$$D = \frac{0.019}{1.36} \times 100 = 1.4$$

35 EXAMPLE 6

(Catamenial Napkin Powder)

40		Percent by Weight	Volume in Cubic Feet
0.25% Hexachlorophene	25	{	{ 0.118
24.75% Talc			0.438
Span 85	0.8		0.013
Tween 80	0.4		0.006
Santocel 54	1.75		0.461
45 Oil	7.55		0.147
"Ucon" propellant 12/14 40/60	64.5		0.730

In the above example, the volume of the active powder at atmospheric pressure is 0.438 cubic foot. The volume at the maximum yield point is 0.148. Therefore, X is equal to $(0.438 - 0.148)$ 0.290. Substituting X in the general formula gives the following:

$$55 \quad 0.29Y = A + B + C + D$$

$$= 0.579 + 0.147 + 0.730 + 0.019$$

$$= 1.475$$

$$Y = 5.08$$

60 Percent by volume of A, B, C, and D to XY

$$A = \frac{0.579}{1.475} \times 100 = 39.3$$

$$B = \frac{0.147}{1.475} \times 100 = 9.9$$

$$C = \frac{0.730}{1.475} \times 100 = 49.5$$

$$D = \frac{0.019}{1.475} \times 100 = 1.3$$

65 70 The following defines various terms used in the examples.

Dicalcium phosphate anhydrous = CaHPO_4 dry powder having a bulk density of 85/90 lbs./cu. ft.

Dicalcium phosphate dihydrate = $\text{CaPO}_4 \cdot 2\text{H}_2\text{O}$ —a crystalline powder having a bulk density of 46 lbs./cu. ft.

Flavor=Any flavor which is oil soluble is a potential agent for these products.

Santocel 54=A silica gel made by Monsanto having a particle size of 0.5-3.0 microns and a bulk density of 3.8 lbs./cu. ft.

"Ucon" propellant 12=Dichlorodifluoromethane, CCl_2F_2 , 70 p.s.i.g. at 70° F.

"Ucon" propellant 114=Dichlorotetrafluoroethane,

$CCl_2F_2-CClF_2$

13 p.s.i.g. at 70° F.

Klearol=Light viscosity white mineral oil. Specific gravity at 60° F. .828/.838. Pour point 30° F. Saybolt viscosity at 100° F. of 55/65.

Span 85=Sorbitan tri-oleate.

Tween 80=Polyoxyethylene sorbitan mono-oleate.

Blandol=Has a specific gravity at 70° F. .850/.860 and a Saybolt viscosity at 100° F. of 80/90.

Carnation=Light viscosity mineral oil which has a specific gravity at 70° F. .835/.845 and a Saybolt viscosity at 100° F. of 65/75.

45 oil=Light viscosity mineral oil which has a specific gravity at 70° F. .815/.825 and a Saybolt viscosity at 100° F. of 40/48.

Aluminum chlorohydrol= $Al_2(OH)_5Cl$.

What is claimed is:

1. A powder dispensing aerosol composition which comprises (1) at least 15 weight percent of an active powder having a particle diameter of at least 15 microns, (2) a powder bulking agent having a particle diameter no larger than the active powder, (3) a non-polar organic liquid, (4) a liquid surfactant, and (5) a propellant; said non-polar liquid, surfactant, and propellant being miscible in all proportions; the combined volume "YX" of said bulking agent, non-polar organic liquid, surfactant, and propellant being 1 to 10 times the difference between the volume of the active powder at atmospheric pressure and the volume of the active powder at maximum yield point; the volume percent "A" of "YX" which is bulking agent, the volume percent "B" of "YX" which is non-polar organic liquid, the volume percent "C" of "YX" which is propellant and the volume percent "D" of "YX" which is surfactant being defined by:

$$YX=A+B+C+D$$

where Y is a number from 1 to 10, X is the difference between the volume of the active powder at atmospheric pressure and the volume of the active powder at maximum yield point, A is 1 to 60 volume percent of YX, B is 2 to 70 volume percent of YX, C is 9 to 67 volume percent of YX, and D is 0.6 to 10.5 volume percent of YX.

2. The composition of claim 1 wherein the active powder has a particle size of from 15 to 100 microns.

3. The composition of claim 1 wherein A is 20 to 40 volume percent of YX, B is 2 to 30 volume percent of YX, C is 10 to 65.5 volume percent of YX, and D is 1.2 to 4 volume percent of YX.

4. The composition of claim 1 where Y is a number between 2 and 5.

5. The composition of claim 1 wherein the nonpolar organic liquid is a hydrophobic oil having a specific gravity of less than 1.9.

6. A powder dispensing aerosol composition which comprises (1) at least 15 weight percent of an active powder having a particle diameter of at least 15 microns, (2) a powder bulking agent having a particle diameter no larger than the active powder, (3) a hydrophobic oil having a specific gravity of less than 1.9, (4) a liquid surfactant, and (5) a propellant; said non-polar hydrophobic oil, surfactant, and propellant being miscible in all proportions; the combined volume "YX" of said bulking agent, non-polar hydrophobic oil, surfactant, and

propellant being 2 to 8 times the difference between the volume of the active powder at atmospheric pressure and the volume of the active powder at maximum yield point; the volume percent "A" of "YX" which is bulking agent, the volume percent "B" of "YX" which is hydrophobic oil, the volume percent "C" of "YX" which is propellant and the volume percent "D" of "YX" which is surfactant being defined by:

$$YX=A+B+C+D$$

where Y is any number from 2 to 8, X is the difference between the volume of the active powder at atmospheric pressure and the volume of the active powder at maximum yield point, A is 20 to 40 volume percent of YX, B is 2 to 30 volume percent of YX, C is .10 to 65.5 volume percent of YX, and D is 1.2 to 4 volume percent of YX.

7. The composition of claim 6 wherein the propellant is fluorochloroalkane having a vapor pressure of 13 pounds and greater per square inch gauge at 70° F.

8. The aerosol composition of claim 6 wherein the active powder has a particle size of from 15 to 100 microns.

9. The aerosol composition of claim 6 wherein Y is a number of 4 to 8.

25 10. The aerosol composition of claim 6 wherein the active powder is at least one of the group consisting of aluminum sulfocarbonate, zinc sulfocarbonate, aluminum chlorohydrol, aluminum sulfate, aluminum chloride, zinc sulfate, zinc chloride, zirconium chloride and zirconium sulfate.

11. The aerosol composition of claim 6 having talc as active powder.

12. The aerosol composition of claim 6 having pumice as active powder.

35 13. The aerosol composition of claim 6 wherein the active powder is at least one of the group consisting of dicalcium phosphate, anhydrous dicalcium phosphate, hydrated dicalcium phosphate, tricalcium phosphate, calcium sulfate and calcium carbonate.

40 14. The aerosol composition of claim 13 wherein the bulking agent is a silica gel having a particle size of 0.5 to 3.0 microns, the surfactant is a liquid nonionic sorbitan surfactant, and the propellant is a fluorochloroalkane having a vapor pressure of 13 pounds and greater per square inch gauge at 70° F.

45 15. A powder dispensing aerosol composition which comprises (1) at least 15 weight percent of an active powder having a particle diameter of 15 to 100 microns, (2) a powder bulking agent having a particle diameter no larger than the active powder, (3) a mineral oil having a specific gravity of less than 0.9, (4) a liquid nonionic surfactant, and (5) a fluorochloroalkane propellant having a vapor pressure of 13 pounds and greater per square inch gauge at 70° F.; said mineral oil, surfactant, and propellant being miscible in all proportions; the combined volume "YX" of said bulking agent, mineral oil, surfactant, and propellant being 2 to 8 times the difference between the volume of the active powder at atmospheric pressure and the volume of the active powder at maximum yield point; the volume percent "A" of "YX" which is bulking agent, the volume percent "B" of "YX" which is mineral oil, the volume percent "C" of "YX" which is propellant and the volume percent "D" of "YX" which is surfactant being defined by

$$YX=A+B+C+D$$

where Y is any number from 2 to 8, X is the difference between the volume of the active powder at atmospheric pressure and the volume of the active powder at maximum yield point, A is 20 to 40 volume percent of YX, B is 2 to 30 volume percent of YX, C is .10 to 65.5 volume percent of YX, and D is 1.2 to 4 volume percent of YX.

16. The aerosol composition of claim 15 having an active powder content of at least 25 weight percent.

17. The aerosol composition of claim 15 as a tooth powder dispensing aerosol containing dicalcium phosphate dihydrate as active powder, a silicia gel having a particle diameter of 0.5 to 3.0 microns as bulking agent and liquid nonionic sorbitan surfactant.

18. A novel aerosol tooth powder having the following composition:

	Percent by weight
Dicalcium phosphate (anhydrous)	2.50
Dicalcium phosphate (dihydrate)	22.50
Silica gel having density of 17.1 lbs./gal	1.75
Mineral oil	10.50
Sorbitan tri-oleate	0.80
Polyoxyethanesorbitan mono-oleate	0.40
Flavor	0.50
Dichlorodifluoromethane	54.95
CCl ₂ F—CClF ₂	6.10
